(57) **CLAIM**

The ornamental design for a microscope slide moisture chamber assembly, as shown and described.

DESCRIPTION

FIG. 1 is a top perspective view of a microscope slide moisture chamber assembly in a closed position showing my new design;

FIG. 2 is a bottom rear perspective view thereof;

FIG. 3 is a front perspective view thereof in an open position; and,

FIG. 4 is an enlarged cross sectional view taken along line 4—4 of FIG. 1.
